CLARENCE A. CAMP, OF OAKLAND, CALIFORNIA

FIRE EXTINGUISHER

Application filed August 1, 1927. Serial No. 209,777.

This invention relates to fire extinguishers and particularly to a chemical type of extinguisher from which a fire extinguishing medium in the form of a dry dust is discharged by means of a non-combustible fire extinguishing gas.

Most chemical fire extinguishers, in use today, employ a fire extinguishing medium in the form of a liquid. A container of one shape or another is usually charged or filled with an alkaline solution and a bottle containing an acid together with convenient means for breaking the bottle so as to mix the acid and alkaline solution when required.

15 The mixing action causes generation of carbonic acid gas and which gas and liquid is accordingly projected on the fire.

Fire extinguishers of this character have numerous objections, among which may be mentioned unnecessary wetting and destruction of goods adjacent the source of fire; damage of goods by smoke created when the liquid solution is applied; production of gases injurious and dangerous to those fighting the fire; and most important of all may be mentioned the limited capacity or quantity of fire extinguishing medium that may be handled by devices of this character; the limited efficiency thereof, as the greater bulk 30 of fire extinguishing material employed is nothing more or less than water, the fire extinguishing chemicals employed being present only in dissolved form in the water and comparatively small amounts are accordingly employed.

The fire extinguisher forming the subject matter of the present application employs a fire extinguishing chemical in its most concentrated form, to-wit: as a solid in the form 40 of dry dust. Efficiency is thereby increased. The amount of chemicals employed is increased. Damage to goods adjacent to the fire zone is eliminated, as the chemicals do not produce smoke, injurious gases, nor wet the goods and the amount of air capable of reaching the fire is also reduced as a non-combustible fire extinguishing gas is generated and employed to project the dust into the zone of fire.

50 The object of the present invention is, ac-

cordingly, that of generally improving and simplifying the construction and operation of fire extinguishers; to provide a fire extinguisher which is capable of projecting a fire extinguishing chemical in its most concentrated form, to-wit: as a solid in the form 55 of dry dust; and, further, to provide a fire extinguisher of this character in which the dry non-combustible fire extinguishing gas may be generated to project the dust into the 60 zone of fire.

The invention is illustrated by way of example in the accompanying drawings, in which—

Fig. 1 is a central vertical longitudinal 65 section of the fire extinguisher.

Fig. 2 is a plan view of the same.

Fig. 3 is a section taken on line III—III of Fig. 1.

Fig. 4 is a cross section taken on the line 70 IV—IV of Fig. 1.

Referring to the drawings in detail and particularly Fig. 1, A indicates in general a cylindrical shaped elongated container constructed of metal or the like, which in this instance is divided into two sections, one to form a compartment B which may be filled with a fire extinguishing medium in the form of a dry dust, while the other compartment, indicated at C, is adapted to be filled 75 with a chemical capable of generating a non-combustible fire extinguishing gas. The container is, in other words, divided into two sections which in this instance may be coupled or connected by a screw or thread 80 connection generally indicated at D. Interposed between the coupling connection D, are a pair of interspaced plates, an upper plate 2 and a lower plate 3. The upper plate 85 is perforated in one or more places, as indicated at 4 and at a point adjacent a discharge pipe generally indicated at 5. The lower plate 3 is perforated in one or more places, as indicated at 6, at a point preferably opposite the perforation 4, and a porous moisture absorbing pad 7 is disposed between the plates, the pad and plates being secured in position when the screw coupling is made.

90 The particular reason for perforating the 95

100

plates 2 and 3, as stated, will hereinafter be described.

The upper portion B of the container may be provided with a handle or the like such as shown at 8, so that it may be grasped and readily handled when in use and discharge pipe 5 is preferably threaded, as at 9, to permit a hose nozzle or the like to be connected therewith. Extending through the lower portion of the container indicated at C, is the shaft or rod 10. This rod projects through a stuffing box 11 so as to prevent leakage and the outer end terminates in the crank arm 12. Suitably secured on the rod substantially centrally of the compartment C, is an eccentric weight 14 and adapted to be placed on opposite sides of the rod 10 at points adjacent the weight 14 are a plurality of acid bottles 15 and 16.

In actual operation, the container is loaded or charged in the following manner: The coupling connection is unscrewed and the plates 2 and 3, together with the pad 7, are removed. Two or more acid bottles 15 and 16 are placed in the compartment C, as illustrated, and a dry chemical, such as bicarbonate of soda, is packed around the bottles and the compartment is filled substantially to its upper end. The bicarbonate of soda performs two functions, first, that of a packing which secures the acid bottles in place and, secondly, that of combining with the acid when it is liberated so as to form carbon dioxide gas. The section B is next inverted and this is completely or substantially filled with bicarbonate of soda in a dry dust-like form. Plate 4, pad 7 and plate 3 are then placed in position and temporarily secured by one or more hook-shaped screws, as indicated at 17. The container B is then placed on top of the container C and the screw coupling is made and the device so filled or charged is ready for use.

In actual operation, when fire is encountered and it is desired to use the extinguisher, it is only necessary to carry it to the zone of fire and to direct the hose or other means connected with the upper end of the discharge pipe toward the fire. Crank 12 is rotated a half a revolution. This forces the weight or eccentric 14 into forcible engagement with the acid bottles 15 and, as the walls thereof are comparatively thin, they are easily broken and the acid is liberated. The reaction between the acid and the bicarbonate of soda in which the bottles are packed produces carbon dioxide gas. The gas escapes upwardly through the perforation 6 in the plate 3, then passes longitudinally through the pad 7 and escapes through the perforations 4 into the upper container B and here creates sufficient pressure to discharge through the pipe 5 and the hose or nozzle connected therewith, carrying with

it dust in such quantities as to completely cover and smother the fire.

It should be noted that the perforations are closely adjacent the lower end of the discharge pipe 5. This is of considerable importance, as it maintains the dust in violent agitation at the point of discharge and thereby prevents packing or clogging of the same. It should also be noted that the pad 7 is preferably constructed of a moisture absorbing material. This is also important, as it is essential that a dry gas be employed. The liberation of the acid in the lower compartment produces a more or less wet gas and it is for this reason that the gas is passed into the pad 7 before it is permitted to enter the dust compartment B and is discharged therefrom.

During actual operation, if it is found that the velocity of the discharging gases is dropping and that sufficient quantities of dust are not being projected, it is only necessary to give the crank 12 another half revolution. This brings the weight 14 into forcible engagement with the second set of bottles which are broken and an additional supply of gas is accordingly afforded as the capacity of the chamber C is so proportioned that the four bottles and the dust contained will generate a minimum of gas, or at least sufficient gas to completely discharge all of the dust contained in the compartment B. The benefits derived from the above described apparatus are as follows:

1. No acids or injurious materials can escape from the generating chamber and by the use of non-injurious fire extinguishing material the extinguisher will be non-injurious to materials or human safety. The action of the fire on the extinguishing materials will not generate any gases that are injurious to human safety and nothing will be expelled from the extinguisher that will cause smoke or other damaging material.

2. By inserting the loose chemicals dry and the acids sealed in glass all the chemicals will be preserved and not deteriorate or lose strength thereby having an extinguisher that holds its effectiveness.

3. By using a dry fire extinguishing stream it spreads into a cloud and tends to float covering a greater area of fire than can be accomplished with a liquid stream from a small extinguisher.

4. By generating non-combustible gases to carry the dust, oxygen is not thrown into the fire, increasing the efficiency of the extinguisher.

5. By using dry extinguishing chemicals which under the heat of a fire generate a non-combustible gas which in turn excludes oxygen and smothers the fire, a greater area of fire can be extinguished than by equal weight of liquid fire extinguishing agents.

making the extinguisher lighter of weight and more practical to use for equal efficiency.

6. By eliminating water the problems of freezing are done away with.

7. The extinguishing stream is not a conductor of electricity nor injurious to mechanical equipment, thereby being more practical around electrical apparatus and less dangerous to human safety or the equipment.

10. The only liquid used is hermetically sealed in glass, thereby eliminating any leaking, spilling or sloshing when carried on boats or other conveyances.

15. This extinguisher may be placed in any position without deterioration.

10. There are no free ingredients to corrode any metal or mechanical parts, thereby eliminating continual attention and maintenance when extinguisher is not used over long periods of time.

11. As this extinguisher is a non-conductor of electricity, as the extinguishing stream is not dense enough to splatter inflammable liquids and as there are no poisonous fumes resulting from the use thereof, this one contrivance will be of protection against all types of fires where now it is necessary to have a special type for electrical uses, inflammable liquids and for use in confined spaces—

20. in other words, this one extinguisher will offer the same protection as is now obtained by three separate types.

12. Further, by using a fire extinguishing chemical in its most concentrated form, that is, as a solid, greater quantities can be carried and handled and greater quantities of carbon dioxide gas will be generated.

Having thus described my invention, what I claim and desire to secure by Letters Patent is—

1. A device of the character described comprising a container divided into two compartments, one of said compartments adapted to be filled with a fire extinguishing chemical in a dry dust-like form and the other adapted to receive gas generating means, a discharge duct in communication with the first named compartment, and a moisture absorbing permeable pad interposed between the compartments and permitting escape of gas from the gas generating compartment to the dust containing compartment and from there to escape through the discharge duct.

2. A device of the character described comprising a container divided into two compartments, one of said compartments adapted to be filled with a fire extinguishing chemical in a dry dust-like form and the other adapted to receive gas generating means, a discharge duct in communication with the first named compartment, the division between said compartments comprising an upper and a lower plate disposed between the compartments, said upper plate being perforated at a point adjacent the discharge duct and said lower

plate being perforated at a point opposite thereto, and a moisture absorbing permeable pad disposed between the plates and permitting escape of gas from the gas generating compartment into the dust containing compartment and from there to escape through the discharge duct.

3. A device of the character described comprising a cylindrical elongated container open at its lower end, said container adapted to be inverted and filled with a fire extinguishing chemical in a dry dust-like form, a discharge pipe extending from the lower end of the container and through the upper end, a second cylindrical shaped elongated container open at its upper end to receive an acid bottle and a chemical which reacts with the acid to form a gas, interengaging screw couplings on each container permitting them to be aligned and connected, moisture absorbing means interposed between the container and separating the chemicals packed in each container, said moisture absorbing means permitting gas to escape from the second named container into the first named container, and means for breaking the acid bottle.
